CLAIM

The ornamental design for a wire retention clip, as shown and described.

DESCRIPTION

FIG. 1 is a front perspective view of the wire retention clip in the open position illustrating our new design; FIG. 2 is a rear perspective view of the wire retention clip of FIG. 1;

FIG. 3 is a right side view of the wire retention clip of FIG. 1, the left side being a mirror image thereof; FIG. 4 is a front view of the wire retention clip of FIG. 1;

FIG. 5 is a rear view of the wire retention clip of FIG. 1; and,

FIG. 6 is a top view of the wire retention clip of FIG. 1, the bottom being flat and unornamented.

FIG. 1

FIG. 2

FIG. 3

FIG. 4

FIG. 5

FIG. 6
